CLAIM

The ornamental design for a segmented end, zipper opening, flat disc weighted bottle cover, as shown and described.

DESCRIPTION

FIG. 1 is a top view of a segmented end, zipper opening, flat disc weighted bottle cover showing my new design;

FIG. 2 is a top isometric view thereof;

FIG. 3 is left side view thereof;

FIG. 4 is a front view thereof, with an indicator for the internal cutaway view and dashed lines showing the material thickness and bottom disc placement;

FIG. 5 is a right side view thereof;

FIG. 6 is a back view thereof with dashed lines showing the bottom disc placement;

FIG. 7 is a bottom view thereof;

FIG. 8 is a partial cross sectional view to show the internal weighted disc of FIG. 8; and,

FIG. 9 is a top isometric view with the bottom of the front cutaway to show the internal disc placement.

The broken lines in the drawings represent unclaimed environmental subject matter and form no part of the claim.
